Application March 6, 1940, Serial No. 322,461
In the Netherlands July 11, 1939

3 Claims. (Cl. 179—171)

This invention relates to a circuit arrangement for the transmission of electrical oscillations which includes at least one electron discharge tube and means for controlling the amplification thereof by a control voltage which acts upon the tube.

In such circuit arrangements a control voltage is usually applied to the input grid of the tube and by which voltage the working slope of the grid voltage-anode current characteristic is acted upon in a desired manner. It has been found in such control circuits that, simultaneously with the desired amplification variation, there occur considerable variations of the working capacity between the various connecting points, more particularly between the grid and the cathode of the tube. Such variations give rise to detuning of the connected oscillatory circuits if the order of magnitude of capacity of the oscillatory circuit can be compared with that of the capacity-variations of the tube. With the control applied the input capacity of the tube between the control grid and the cathode may in many cases vary by 1.5 mmf. With a capacity of the oscillatory circuit of 75 mmf., the value of the detuning involved thereby may amount to about 1% of the initial resonance frequency of the tuned circuit. When the connected tuned circuits have a small damping and a corresponding high selectivity, such detuning manifests itself in a very annoying manner.

The present invention permits the said variations of the working capacity to be avoided in controlling the amplification. According to the invention the variations in capacity caused by amplification control means between two connecting points of the tube, for instance between the input grid and the cathode, are compensated for by means of a variable condenser controlled by the said means.

According to another feature of the invention the variation of the ohmic component of the tube impedance existing between the connecting points of the tube can also be made up for. To this end a fixed resistance is preferably connected in series with the variable condenser.

The invention will be more fully explained by reference to the accompanying drawing wherein,

Fig. 1 represents a circuit arrangement in which amplification is controlled manually and the correcting condenser is operated at the same time,

Fig. 2 shows a circuit arrangement wherein control of amplification and the correcting condenser is effected automatically.

In the circuit arrangement shown in Fig. 1 the signal oscillations to be amplified, which are applied to the terminals of an oscillatory circuit 1, are supplied through a condenser 2 to the signal grid 3 of an amplifying tube 4 provided with variable amplification. Amplification control of tube 4 is effected by supplying a control voltage to the signal grid 3 through a resistance 5. The amplified oscillations are supplied to an inductance 6 disposed in the anode circuit of tube 4, and with which inductance is coupled the remaining part of the circuit arrangement (not represented in the drawing). The control voltage required for controlling the amplification of tube 4 is taken from a resistance 8 in the cathode lead of tube 4. The resistance 8 is furnished with a sliding contact 7 and is bridged by a condenser 9 having a negligible impedance for alternating currents of the frequency to be amplified.

Upon controlling the bias of the signal grid 3 of tube 4 the space charge in this tube varies which involves at the same time a variation of the input capacity of tube 4. In order to compensate for this variable input capacity a variable condenser 10 is connected between the signal grid 3 of tube 4 and the grounded electrode of condenser 9. This variable condenser 10 is mechanically connected to the sliding contact 7 of resistance 8. The mechanical coupling is indicated by a dotted line 11. When controlling the amplification by displacing the sliding contact 7 the condenser 10 is at the same time controlled in such manner that the input capacity of tube 4 remains at least substantially constant.

In the circuit arrangement shown in Fig. 2 corresponding parts of Fig. 1 bear the same reference numerals. In Fig. 2 the amplification of tube 4 is not controlled manually but automatically. For this purpose the signal grid 3 is connected through the resistance 5 to a lead 12 which is connected to a signal rectifier for automatic volume control (not represented). The letters AVC designate the connection to a usual automatic volume control rectifier. During amplification control the input capacity and at the same time the anode direct current of tube 4 vary. The anode circuit includes a galvanometer device 13 which is mechanically coupled with the variable condenser 10 for compensation of the input capacity, and which mechanical coupling is indicated by a dotted line 14. A fixed resistance 15 is connected in series with the variable condenser 10. This resistance 15 serves to make up for the damping which varies

with the amplification exerted by the input impedance of tube 4 on the oscillatory circuit 1.

When the negative bias of the signal grid 3 increases the input capacity of tube 4 decreases, and at the same time the damping exerted on the circuit decreases. In order to make up for the decreasing input capacity of tube 4 the variable condenser 10 is controlled by the galvanometer device in such a manner that the capacity increases. As a result thereof the resistance 15 connected in series with the variable condenser 10 exerts a damping effect on the oscillatory circuit, and which damping increases with increasing negative bias and makes up for the damping which is exerted by tube 4 on the oscillatory circuit 1 and decreases with increasing negative bias.

What is claimed is:

1. In a signal transmission system having input and output terminals, at least one electron discharge tube provided with at least a signal control electrode, cathode and output electrode, means connecting said input terminals to said control electrode and cathode, means coupling the output electrode and cathode to said output terminals, means for adjusting the potential difference between said control electrode and cathode thereby to vary the gain of said tube whereby the capacity existing between said control electrode and cathode varies, a device connected between said input terminals providing a compensating capacity thereacross, and means jointly operative with changes in said potential difference for varying the magnitude of said compensating capacity in a sense to prevent said first capacity from being effective across said input terminals and a resistor in series with said device whose damping effect between said input terminals increases with increase of the compensating capacity magnitude.

2. In a tunable signal amplifier of the type having a tube provided with at least a cathode, signal grid and output plate, a tunable signal input circuit connected between the grid and cathode, and means for varying the grid bias to adjust the gain of the tube; an improvement for preventing the capacity component of the grid to cathode impedance of said tube, which varies in value with gain variation, from affecting the resonant frequency of said input circuit, said improvement comprising an adjustable capacitance device operatively associated with said input circuit to oppose the effect of said component, and means for controlling said device in response to operation of said bias varying means and in a sense to compensate for variations in the magnitude of said component, said device having a resistor of predetermined value in series therewith across said input circuit, and said resistor compensating for variations in the resistive component of said impedance.
3. A signal amplifier of the type having a resonant input circuit, said amplifier comprising a tube having at least a signal grid, cathode and output electrode, means for varying the bias of said grid over a range such that the inherent tube grid to cathode impedance variation affects the input circuit response characteristic, means connected in shunt across said input circuit for providing a compensatory impedance thereacross, and means for control of said shunt means in response to said varying means, said inherent impedance having a capacity component and a resistive component, and said shunt means including an adjustable capacity in series with a resistor whose damping effect on said input circuit increases with increase of magnitude of said adjustable capacity.
